(57) **CLAIM**

The ornamental design for an exercise assembly, as shown and described.

DESCRIPTION

Additionally, for purposes of facilitating understanding of the context and usage of the apparatus for which design protection is claimed herein, reference is hereby made to U.S. patent application No. 12/126,924, which published as patent application Publication No. U.S. 2008/0318743 on Dec. 25, 2008, each of which are incorporated herein by reference. All of the material from application 12/126,924 and corresponding Publication No. U.S. 2008/0318743 which is essential to the claimed design is included in this application. Any material in application 12/126,924 and corresponding Publication no. U.S. 2008/0318743 which is not present in this application forms no part of the claimed design.

FIG. 1 is a perspective view of an exercise assembly showing my new design, wherein said view is further representative of the opposite perspective view thereof;

FIG. 2 is an elevational view of one end of the exercise assembly of FIG. 1, wherein said view is further representative of the opposite end view thereof;

FIG. 3 is a top plan view of the exercise assembly of FIG. 1; FIG. 4 is a bottom plan view of a front of the exercise assembly of FIG. 1;

FIG. 5 is a front elevational view of the exercise assembly of FIG. 1, wherein said view is further representative of the rear elevational view thereof; and,

FIG. 6 is a perspective environmental view of the exercise assembly of FIG. 1 showing the unclaimed handles and resistance bands attached, wherein said view is further representative of the opposite perspective view thereof.
